ALARM-WATCH

Raymond Gilbert Ryser, Renan, Switzerland, assignor to
Fabrique de boites de montres S. Gruber S.A., Renan,
Bern, Switzerland

Filed Apr. 12, 1960, Ser. No. 21,802

Claims priority, application Switzerland Sept. 30, 1959
5 Claims. (Cl. 58—57.5)

This invention relates to alarm watches and in particular to alarm wrist-watches of the type comprising a movement with a particular stem to set the alarm time of the watch, the said stem being located at the periphery of the movement and extending in a direction perpendicular to the movement axis, and it relates even more particularly to alarm wrist-watches of this type in which a control member outside the watch case can be actuated to turn said stem.

Several examples of alarm wrist-watches of said type are already known in the art. Most of the watch movements used thereby are provided with a couple of stems to ensure all the functions of the watch, i.e. winding up the watch movement and the alarm mechanism, setting the time indicating hands and the alarm time indicator indicating the time at which the alarm mechanism will operate, locking releasing and stopping the alarm mechanism. One of said stems generally permits, in a pushed position, to wind up the watch movement, when it is driven in one direction, and to wind up the alarm mechanism, when it is driven in the other direction, and, in a pulled position to set the time indicating watch hands, while the other stem permits, in a pushed position, to set the time at which the alarm mechanism must operate. In these known movements the alarm mechanism is actually locked, when the alarm time setting stem is pushed. To release this alarm mechanism so that it may operate at the desired time, this alarm time setting stem must be pulled. Moreover, when the alarm mechanism is running, it can be stopped at will be pushing said alarm time setting stem.

The alarm wrist-watches made till now with said movements are provided with two crowns each fixed to one of said stems at the periphery of the watch case to control the operation of said stems. These alarm watches have however the drawback that setting the alarm time is a rather cumbersome operation. Since the alarm time indicator can only be rotated in one direction, the corresponding crown must often be caught many times until the alarm time indicator is set in the desired position, and it sometimes occurs that said indicator is moved beyond the desired position, so that it has to be driven once more around the dial. The owner of such a watch who would desire to use it frequently, for instance, to remind himself of the parking time of his car, would soon be tired by said setting operations of the alarm mechanism of his watch.

It is now an object of this invention to provide an alarm watch in which setting the alarm time is very easy.

Another object of this invention is to provide an alarm watch of the type indicated above with a control member mounted on the watch case for rotary motions therearound, said control member ensuring the rotary motions of the alarm time setting stem by means of a speed reducing mechanism comprising planetary means and a differential motion transmitting member.

The watch movements known of the type indicated would indeed not enable actuating a pinion fixed on to said alarm time setting stem directly by means, for instance of a rotary bezel provided either with a spur gear or with a crown wheel toothed, since it is not possible, with the existing alarm wrist-watch movements, to make a pinion great enough to obtain a satisfactory transmis-

2

sion ratio between a rotary bezel and the alarm time indicator. In other words, the precision of the alarm time setting operation would be questionable, since a very small rotary motion of the bezel would produce a rather great displacement of the alarm time indicator. A speed reducer is therefore advantageously provided between a control member rotatably mounted around the watch case and the alarm time setting stem, if the latter is to be made adjustable with a satisfactory precision by means of a rotary bezel.

In most of the movements with alarm mechanism known in the art, the alarm time setting stem and the usual winding and hand setting stem of the watch are located near one another, and the alarm time setting stem carries a control button or crown at the periphery of the watch case to enable moving this alarm time setting stem axially from its pushed position to its pulled position. As already indicated above, said alarm time setting stem enables setting the alarm time indicator when it is pushed, while in pulled position it merely releases the alarm mechanism and enables the latter to run down as soon as the watch hands indicate the same time as said alarm time indicator. Now, to pull said alarm time setting stem outward the casing with the alarm watches known in the art, the control button or crown usually fixed to said alarm time setting stem must be arranged so that it can be grasped and it must therefore be provided with a portion projecting from the watch case outer surface, if said pulling operation is to carry out in an easy manner.

This solution has, however, not only the drawback of producing a bad aesthetical effect but also that of exposing said button or crown and the stem to which it is fixed to some dangers. It is indeed a matter of fact that all parts projecting from a watch case, and in particular from a wrist-watch case, often remain gripped to foreign objects, such as for instance clothes sleeves.

It is therefore also an object of this invention to provide an alarm watch of the type indicated so as to avoid said drawbacks.

40 A further object of this invention is to take benefit of the fact that the alarm time setting stem is not actuated in rotation manually, but by means of a control member rotating around the watch case, and to insert accordingly the control button or crown fixed to this stem entirely within a watch case lodging, the axial displacements of said stem being ensured by means of a lever extending on both sides of the winding and hand setting stem, said lever having one end cooperating with said control button or crown and carrying a button at its other end so that pushing said button will produce an outward motion of said alarm time setting stem.

Still further objects of the invention will become apparent in the course of the following description.

55 Four embodiments of the watch improved according to the invention are represented diagrammatically and by way of example in the drawings affixed to this specification, wherein like reference numerals designate identical parts throughout the same.

In the drawings:

60 FIG. 1 is an enlarged part sectional view taken along line I—I of FIG. 4;

FIG. 2 is a part elevational view with a member cut away, taken from the left of FIG. 1;

65 FIG. 3 is a cross-section on a reduced scale taken along line III—III of FIG. 1;

FIG. 4 is a plan view on the same scale as FIG. 3 of the first embodiment;

FIG. 5 is a cross-section analogous to that of FIG. 1 but showing the second embodiment;

70 FIG. 6 is a cross-section analogous to those of FIGS. 1 and 5 of the third embodiment;

FIG. 7 is a plan view with some parts broken away and other in section of the fourth embodiment, and

FIG. 8 is a partial cross-section on a greater scale and along line VIII—VIII of FIG. 7.

The alarm wrist-watches represented in the drawings are all provided with a movement of the well-known type indicated above. The operations of this movement are ensured as shown in FIG. 4 by means of two control buttons or crowns 1 and 2 provided at the watch periphery. 1 is the usual crown fixed at the end of the winding and hand setting stem. In its pushed position this crown 1 enables winding up the motor spring of the watch, said spring driving both the watch movement and the alarm mechanism. In said pushed position the crown 1 could also be arranged so that a rotation thereof in one direction would ensure winding up the motor spring of the watch, and so that a rotation of crown 1 in the opposed direction would wind up another motor spring arranged for driving the alarm mechanism. Moreover, this crown 1 enables setting the time indicating hands constituted by the hour hand 3 and the minute hand 4 of the watch, when it is pulled out of the watch case. 2 is a control button also fixed to a control stem described hereinafter with more details. It ensures setting the alarm time indicator constituted by hand 5, when it is in its pushed position, and releasing the alarm mechanism, when it is in its pulled position.

In contradistinction to what has been done in the alarm watches made till now with said known movements, only the winding and hand setting stem of the watch according to the invention is actuated by a usual crown. In the four embodiments described in detail hereinafter the alarm time setting stem is controlled by a rotary bezel.

In the first embodiment the details of which are more particularly represented in FIGS. 1 to 3, the watch movement 6 is located together with a usual dial 7 in a caseband 8 carrying a glass 9 and a bottom 10. A peripheral flange 11 of the latter presses on a gasket 12 under the action of a ring 13 screwed on a threaded portion of the caseband 8. Two bores are provided across the wall of this caseband to form passages, on the one hand, for the stem winding both the watch movement and the alarm mechanism and setting the time indicating hands 3 and 4, and, on the other hand, for a stem 14 ensuring setting the alarm time indicating hand 5 and permitting the alarm mechanism to run down when the hands 3, 4 and the hand 5 indicate the same time. The latter function of stem 14 is ensured when said stem is pulled out of the watch case. In its pushed position represented in FIG. 1, stem 14 is operatively connected to the alarm time indicating hand 5 so that a rotary motion of stem 14 in a predetermined direction drives hand 5 in the allowable direction, i.e. counterclockwise. A button 15 made in one piece with a tapped sleeve 16 is fixed on the screw-threaded end portion of stem 14. A tight closure between sleeve 16 and the case band 8 is ensured by means of a gasket 17 compressed in a tapped lodging of the caseband 8 by means of a screw-threaded ring 18. A toothed pinion 19 is set with force fit on to sleeve 16 so as to be fixed for rotary motions with respect to stem 14. Pinion 19 and button 15 are completely engaged in a cylindrical lodging 20 of the caseband 8, when the stem 14 is in its pushed position.

To enable pulling the stem 14 outward in an axial direction, a concave lathe-turned portion 21 is provided in the lower part of the caseband 8 all round the latter. Moreover, the pinion 19 is made with an outer diameter smaller than that of button 15. It is thus possible to grip the latter by engaging a fingernail between the caseband 8 and the button 15 to pull the latter outward, until it reaches the position represented in dot-and-dash lines in FIG. 4.

In the axial position represented in FIG. 1 a motion transmitting ring member 22 is in meshing relation with

the pinion 19 by means of a crown wheel toothing as shown in FIG. 2. This member 22 is located in an annular space extending around the watch case, and comprised between a rotary bezel 23 and the caseband 8.

5 The member 22 can be driven in rotation round the caseband 8 by means of balls 24, which also form a ball-bearing of bezel 23. The inner ball race of this bearing is formed by a pair of truncated conical surface portions 25 cut all round the caseband 8. The outer ball race of said bearing is constituted by a rounded groove 26 provided in the bezel 23. As shown in FIG. 1 the groove 26 is so arranged as to form an annular inwardly and downwardly extending rim 27 coming in contact with a ball portion 25 situated below the plane defined by the centers of said balls. The rim 27 thus serves as axially retaining means for the bezel 23. Assembling and disassembling this bezel 23 can accordingly be performed as with a bezel snap fitted on to the caseband.

20 The balls 24 are regularly distributed all round the caseband 8 as shown in FIG. 3. They are held in fixed positions with respect to member 22 by means of lodgings 28 provided in member 22 for these balls 24. The lodgings 28 are of course made large enough to leave the balls 24 rotating freely therewithin.

25 When the bezel 23 is driven in rotation round the caseband 8, the balls 24 roll without slipping between the inner and outer races 25 and 26 of the caseband 8 and of bezel 23, respectively. By rolling that way, the balls 24 drive member 22 in rotation round the caseband 8. The angular speed of this member 22 is however smaller than that of bezel 23. If the balls 24 are very small, the angular speed of member 22 is almost half that of bezel 23.

30 The speed reduction ensured by the differential motion transmitting device described enables a very precise setting of the alarm time indicating hand without altering anything in the connecting means provided between stem 14 and hand 5, the transmission ratio of which is well determined in the movements known in the art. In these movements the transmission ratio between stem 14 and hand 5 is indeed chosen so that stem 14 has to be driven three or four times on itself to drive hand 5 once around the dial. Moreover, if the pinion 19 is made as large as possible within the limits of the watch's height, the transmission ratio between the motion transmitting member 22 and this pinion 19 is 1 to 10, i.e. the pinion 19 makes ten revolutions for one of the member 22 round the caseband 8. Since this member 22 is moving approximately half as quick as the bezel 23, it follows that pinion 19 makes almost five revolutions when the bezel 23 is driven once around the caseband 8. As a consequence of these transmission ratios, to move the hand 5 through a predetermined angle, the bezel 23 has to be moved approximately through the same angle around the caseband 8.

35 Experiments have shown that the transmission ratio obtained between the bezel 23 and the hand 5 enables setting this hand 5 in an extremely precise and quick manner by means of the bezel 23, whereas a rotary bezel provided with a toothing meshing directly with pinion 19 would not enable setting of the hand 5 with a precision greater than a quarter of an hour after or before the time at which the alarm mechanism should begin running.

40 To render driving the bezel 23 in rotation around the caseband more easy, grooves 29 are cut in the upper face of this bezel.

45 Although the fixing means of the bezel 23 constituted by the rim 27 considerably facilitate mounting the driving device of pinion 19 shown in FIG. 1, it may also be desirable to mount the rotary bezel in such a manner that the ball-bearing described cannot be opened by everybody, because of the danger of losing the balls. This danger is avoided in the second embodiment shown in FIG. 5.

50 In this second embodiment the inner ball race is cut

in an independent ring 30. The outer ball race is here constituted, like the inner race, by a pair of truncated conical surface portions which are located, the first one on the rotary bezel 31, and the second one, on a ring 32 rigidly secured to the bezel 31 by means of screws 33.

To assemble this ball-bearing, the two members 30 and 31 are set into one another and the balls 24 are introduced between these two members. The ring 32 is then fixed to the bezel 31. Mounting this ball-bearing on the watch case can be performed by setting first the motion transmitting member 22 in place and then by pressing the ring 30 with force fit on to a cylindrical portion 34 of the caseband 35.

With the exception of the elements described above this second embodiment is identical with the first one and it functions likewise. If the ball-bearing described becomes defective a watchmaker can repair the watch without any difficulty by removing the unit constituted by members 30, 31 and 32 and by setting a new unit on the watch case.

Instead of using a speed reducer with differential motion transmitting member in which the planetary means are constituted by balls, it is also possible to use a similar device in which the planetary means are constituted by pinions as shown in the third embodiment (FIG. 6). In this embodiment the stem 14 of movement 6 also carries a button 15 provided with a sleeve portion on to which a toothed pinion 36 provided with a bearing surface 37 is fixed with force fit. This pinion 36 has, however, a greater diameter than that of button 15 but the bearing surface 37 is smaller than this button. It forms thus the bottom of a groove extending between pinion 36 and button 15 and into which a fingernail can be introduced to move button 15 in axial direction and to carry thus stem 14 from its pushed position (represented in FIG. 6) into its pulled position.

Pinion 36 is in meshing relation with a toothed motion transmitting member constituted by ring 38. Bores 39 are provided in this ring 38 to receive pivots 40 made in one piece with pinions 41. These pinions 41 have the same function as the balls described in the two first embodiments. They are driven in rotation around pivots 39, on the one hand, by means of a ring 42 provided with an external toothed and set with force fit around an annular projection 43 of a piece 44, and, on the other hand, by an internally toothed ring 45 set with force fit into a cylindrical lodging of a rotary bezel 46. This bezel 46 is mounted for rotary motions on the caseband 47 by means of an annular rim 48 snap fitted on a corresponding portion of the caseband 47. As in the second embodiment piece 44 is set with force fit on to a cylindrical surface portion 34 of the caseband 47.

In the watch represented in FIGS. 7 and 8 the stem 14 actuates an alarm time indicator constituted by a disc 5a coaxial to the watch, when it is driven in rotation around its axis. This stem 14 carries an actuating member 2 first comprising a tapered sleeve 16a screwed on a threaded portion of stem 14. Sleeve 16a is provided with an outwardly extending toothed rim 55. When the stem 14 is in pushed position, this toothed rim 55 is in meshing relation with a motion transmitting member 22a driven in rotation by a rotary bezel 23a. The actuating member 2 comprises moreover a button 15a having a cylindrical central projection 56 set with force fit into the axial opening of sleeve 16a.

The passage of the winding and hand setting stem across the caseband 8a is tightly closed by a gasket of well-known type inserted between crown 1 and tube 51. This tube 51 is provided with a central annular outer rim 52, and it has its inner end set with force fit into a radial bore of the caseband 8a.

Another radial opening is also provided across said caseband for the stem 14. This second opening has an inner portion the diameter of which is somewhat greater than that of the sleeve 16, and an outer enlarged portion

which forms a tapped lodging to receive a tightening gasket 17 and a screw-threaded ring 18 holding said gasket in place.

As already described above the stem 14 and consequently the sleeve 16a as well as the button 15a are fixed to one another and they can be set in two different axial positions. While moving said stem from its pulled position to its pushed position can be ensured by merely pressing on the buttons 15a, it is not possible to pull this button outward to move the stem 14 from its pushed position to its pulled position, since said button is flush with the outer surface of the caseband 8a when it is in its pushed position.

To enable the outward motion of said button and of the stem 14 fixed thereto, a control lever 49 having an L-shaped cross-section is extending on both sides of the winding and hand setting stem. At its end 50 this lever 49 is provided with two fingers 57 and 58 extending on both sides of sleeve 16a and caught between the toothings 55 of this sleeve 16a and a ring 60 axially pressed between sleeve 16a and button 15a. The rocking motions of lever 49 are thus transformed in axial movements of member 2 without preventing the latter from rotating in its pushed position around its axis to set the alarm time indicator 5a.

A central opening 59 is provided in this lever 49 to permit engaging the latter around the upper portion of tube 51, on to rim 52 thereof. The tube 51 serves as guiding means for the lever 49 by preventing the latter from any transversal motion with respect to tube 51.

In axial direction the lever 49 is also held in place on tube 51, since the axial displacements of said lever are limited, on the one hand, by the annular rim 52, and, on the other hand, by the winding and hand setting crown 1.

The other end of lever 49 carries a control pushing button 53 fixed on to its outer face. Moreover, an elongated lodging 54 is provided in the outer side face of caseband 8a. This lodging 54 extends on both sides of the winding and hand setting stem. The lever 49 is entirely located in this lodging 54, so that the outer face of lever 49 is flush with the adjacent portions of the outer face of the caseband 8a. The lodging 54 is entirely filled by lever 49 so that it is not apparent. The outer surface of this lever 49 is also finished in the same way as that of the caseband 8a so that the lever 49 does not injure the appearance of the watch case.

When the stem 14 is in pushed position, the rotary bezel 23 enables driving the indicator 5a in the same manner as in the embodiments described above. If the control button 53 is then pressed inwards, the lever 49 bearing by the edges of its opening 59 on the annular rim 52 of tube 51 rocks and its end 50 carries the actuating member 2 into its pulled position.

When it is desired to move the actuating member 2 from its pulled position into its pushed position, for instance when the alarm mechanism of the watch is running in order to stop it, the button 15a need only be pressed, and the lever 49 will then be brought back in the position represented in FIG. 7.

It will be observed that the buttons 53 and 15a are only actuated by pressing so that there is no need of making them so that they project in a substantial manner from the watch casing. On the contrary, they can be given a form which does not injure the appearance of the watch and so that they do not risk being caught by foreign objects coming in contact with the watch.

While several embodiments of the invention have been described in detail with reference to the accompanying drawings, it will be understood that various changes in the shape, sizes and arrangement of parts could be resorted to without departing from the spirit of the invention or sacrificing the advantages thereof.

I claim:

1. In a watch with an alarm mechanism, in combination, a case having an axis; a control member mounted on

said case for rotary motions coaxially thereto; a control lever mounted on said case at the periphery thereof for rocking motions about a center portion; a movement located in said case and provided with time indicating hands, an alarm time indicator, a first stem mounted in said movement for rotary and for shifting motions to wind up both the watch movement and the alarm mechanism and to set the time indicating hands, said first stem extending in a direction perpendicular to said case axis, and a second stem also mounted in said movement for rotary motions and for shifting motions in an axial direction from a pushed position to a pulled position and vice versa, said second stem extending in a direction perpendicular to said case axis and being arranged at one side of said first stem to set said alarm time indicator while locking said alarm mechanism when said second stem is in one of said axial positions and to release said alarm mechanism when said stem is in its said other axial position; an actuating member on said second stem engaged by one end of said control lever to move said second stem from its pushed position to its pulled position upon a pressure exerted on the other end of said lever; and a speed reducing mechanism with planetary means inserted between said control member and said case and comprising a motion transmitting member capable of rotating coaxially to said case to drive said second stem in rotation, when said second stem is in its alarm time setting axial position, upon a rotation of said control member.

2. In the alarm watch of claim 1, said control lever carrying a control pushing button at its end opposed to that which engages said second stem. 30

3. In the alarm watch of claim 1, an elongated lodging provided at the periphery of said case on both sides of said first stem to receive said control lever, said control lever being entirely engaged in said elongated lodging and being flush with said case to hide said elongated lodging. 35

4. In the alarm watch of claim 3, a tube fixed to said case and forming a passage for said first stem, an annular rim around said tube, an opening provided in the center portion of said control lever to permit engaging said control lever around said tube on said rim thereof to enable said rocking motions.

5. In an alarm wrist-watch the combination of: a watertight case comprising a caseband having an axis and being formed with a cylindrical wall portion in its upper portion; a bezel comprising a cylindrical wall portion extending coaxially to and around said cylindrical wall portion of the caseband; a movement located in said case and provided with an alarm time setting stem mounted in said movement for rotary motion and extending in a direction perpendicular to said axis of the caseband; and journaling and holding means arranged exclusively on said bezel and on said caseband and located therebetween both to journal the bezel around said caseband and to hold it axially in place thereon, said journaling and holding means comprising planetary means inserted between said wall portions of the bezel and of the caseband, said planetary means forming part of a speed reducing mechanism and said speed reducing mechanism further comprising a motion transmitting member capable of rotating coaxially to said caseband and arranged for establishing an operative connection between said bezel and said stem.
